UNITED STATES PATENT OFFICE.

NATALE SALVUCCI, OF DETROIT, MICHIGAN, ASSIGNOR OF ONE-HALF TO JOHN W. HEADLEY, JR., OF KANSAS CITY, MISSOURI.

WRENCH.

Application filed January 31, 1925. Serial No. 5,964.

This invention relates to improvements in wrench constructions.

The primary object of this invention is the provision of an improved wrench, which is of a relatively simple, and practical nature, which will enable the same to be universally used, and which embodies an improved construction for quickly and conveniently adjusting the same, over a wide range, without the conventional slow and tedious adjustments.

A further and important object of this invention is the provision of an improved wrench construction capable of a wide range of adjustments merely by use of the wrench; the handle functioning as a lever for movement of the jaws in relation to each other as the wrench is applied to an article, such as a bolt or a nut, to rotate the same.

20 A further object of this invention is the provision of an improved wrench of the above described character, which has a ratchet-like motion, tending to cause the jaws to grip together upon an object at the intervals between the tightening movements.

Other objects and advantages of this invention will be apparent during the course of the following detailed description.

In the accompanying drawing, forming a part of this specification, and wherein similar reference characters designate corresponding parts throughout the several views,

Figure 1 is a side elevation of the improved wrench, showing the same gripping a relatively large nut.

Figure 2 is a cross sectional view taken substantially on the line 2—2 of Figure 1.

Figure 3 is a bottom edge view of the improved wrench.

40 Figure 4 is a fragmentary view, partly in section, showing the wrench jaws in a differently adjusted relation than that illustrated in Figure 1, gripping a relatively small nut or like object.

45 Figures 5 and 6 are perspective views of a pair of jaws used in connection with the wrench.

In the drawing, wherein for the purpose of illustration is shown only a preferred embodiment of the improved wrench, the letter A may generally designate the improved wrench, which may consist of a pair of relatively movable jaws B and C, which may be respectively designated male and female wrench jaws; and a lever-handle D.

The jaw B preferably includes the jaw head 10, providing a nut engaging face 11. Integrally connected with the jaw head 10 are a pair of spaced parallel shanks 13 and 14, providing the space 15 therebetween adapted to receive a portion of the jaw C to be subsequently described. Each of the shanks 13 and 14 includes an upper opening 16 transversely provided through said shanks, which are in aligning relation; and furthermore each of said shanks 13 and 14 includes a lower opening 17, in aligning relation with each other transversely of said shanks. Each of these shanks 13 and 14 are in right angled relation with respect to the jaw face 11, and the outer surfaces of said shanks are in a plane just inwardly of the outer surfaces of the jaw head 10, providing abrupt stop shoulders 20 adapted to cooperate in limiting the closed movement of the jaws B and C as will be readily apparent. At their lower forward corners the shanks 13 and 14 are convexly arcuate, as at 21, somewhat reducing in width the free ends of said shanks, to facilitate their introduction into grooves provided therefor in the jaw C.

Referring to the jaw C, the same includes a jaw head 25, provided with a top nut engaging face 26. The jaw C furthermore includes the body 27 integrally connected with the head 25, and which body 27 at opposite sides thereof is provided with the guide grooves 28 and 29, disposed at right angles to the jaw face 26, and adapted to slidably receive therein the shanks 13 and 14 respectively of the jaw B. At the opposite sides of the jaw head 25, the same is inwardly recessed, as at 30, and transversely through said jaw head 25 from one recessed side 30 to the opposite recessed side, an opening or passageway 31 is provided, which is adapted to receive a pivot pin 32, which pivotally connects the lever-handle D to the jaw C, and as will be subsequently described.

In the web 35, which constitutes a part of the jaw body 27 between the grooves 28 and 29, an elongated slot 36 is provided, extending longitudinally of the grooves 28 and 29, and parallel with the run thereof. At the upper corner of the jaw C, a lug 39 is integrally connected to the body 27, extending outwardly of the rear surface 40 of the jaw C; the same being provided for a purpose which will be subsequently described.

The lever-handle D of the improved

wrench A preferably includes the relatively long hand engaging body 50, of any approved length, which at the forward end thereof is provided with the spaced parallel 5 forwardly extending jaw attaching shanks or fingers 53 and 54, providing a space 55 therebetween, adapted to receive portions of the jaws B and C, as will subsequently appear. At their forward ends the fingers or shanks 53 and 54 are preferably provided with aligning openings 57 and 58 respectively, which are adapted to align with the passageway 31 in the jaw head 25 when the handle D is assembled to the jaw C, for the 10 purpose of receiving the pin 32 therethrough in order to pivotally connect the handle to the jaw C. In this position of parts, it is to be particularly noted that the ends of the handle shanks or fingers 53 and 54 extend 15 into the recesses 30, as is illustrated in Figure 2 of the drawing, and the outer surfaces of the fingers 53 and 54 lie flush with the outer surfaces of the jaw head 25. The pin 32 is of any approved character, and at its 20 outer ends may be riveted, or peened over the outer surfaces of the fingers or shanks 53 and 54, similar to that illustrated in Figure 2 of the drawing, in order to pivotally connect the handle D to the jaw C, in the relation described. The body 27 of the jaw C, of course, is then disposed in the space 55, and the rear surface 40 of the jaw C is spaced from the facing surface 59 of the handle part 50 sufficiently to permit a free 25 oscillative or pivotal movement of the handle D and jaw C. In this relation of parts, the lug 39 is disposed just above the top edge of the handle fingers or shanks 53 and 54, for a purpose which will be subsequently 30 mentioned.

Referring to the assembly of the jaws B and C, the shanks 13 and 14 of the jaw B, are slipped downwardly into the guide grooves 28 and 29 of the jaw C, and in this 35 position the outer surfaces of the said shanks 13 and 14 lie flush with the outer surfaces of the bottoms of the recesses 30, and of course lie flush in sliding engagement against the inside surfaces of the handle fingers or shanks 53 and 54, as is illustrated in Figure 40 2 of the drawing. In this assemblage of parts the transverse openings 17 and 18 are in position to align with the slot 36 as the jaws B and C are relatively moved away 45 from and toward each other.

The handle shanks 53 and 54 are preferably provided with a pair of transversely aligning slots 65—66 respectively therealong, which extend substantially longitudinally of 50 their respective shanks or fingers 53 and 54, and the run of which slots 65 and 66 is arranged transversely to the run of the slot 36 and the guide grooves 28 and 29 of the jaw C. The jaw B is connected for movement to 55 the handle D, and to this end a connecting

pin 70 is provided, adapted to extend transversely through the slots 65 and 66; thru either the openings 16 and 17; and through the longitudinal slot 36 of the jaw B, in order to properly connect the parts B, C and 70 D of the wrench A. The upper pair of aligning openings 16 of the shanks of the jaw B are only utilized when it is desired to secure a range of adjustment for gripping small articles, such as the nut F illustrated 75 in Figure 4 of the drawing. The lower pair of openings 17 of the jaw shanks 13 and 14 are used for securing a range of adjustment for gripping larger articles or nuts, such as the nut G illustrated in Figure 1 of the 80 drawing.

It is thus to be noted that the pin 70 should be detachable, so that the jaw C may be selectively connected to the jaw C and handle D, in the proper relation, thru either the 85 openings 16 or 17. To this end the pin 70 at one end thereof is provided with an integral enlarged head 71 adapted for abutment at the outer surface of the shank 53, and at the opposite end thereof is provided with an 90 annular groove 72, adapted to receive a detachable split washer 73, which when it is in said groove 72 extends circumferentially outwardly to provide a head, in effect, for the pin 70; the outer periphery of said washer 95 being of greater diameter than the width of the slot 66, in order that the pin 70 may pivotally and slidably connect the parts of the wrench, without liability of detachment thereof.

In this relation of the jaws and the handle D, it is to be particularly noted that the lever-handle D is obtusely arranged with respect to the direction of movement of the jaw B with respect to the jaw C; the obtuse angle occurring between the head end of the jaw B and the upper edge of the handle D, which is considered to be the most effective 105 arrangement of parts for the wrench A.

From the foregoing description of the assemblage of the jaws and handle of the wrench A, it is believed that the operation will be obvious. Assuming the pin 70 to be connected through the openings 17 of the jaw B, the wrench is in position to engage relatively large nuts, such as the nut illustrated 110 in Figure 1, and upon the application of pressure on the handle D away from the head 10 of the jaw B, the lever-handle D will pivotally move on its pin 32 with respect to the jaw C, and will of course urge the pin 70 downwardly along the slot 36 of the jaw B and pull the shanks 13 and 14, and consequently the jaw B in direction towards the jaw C, for clamping the heads of the jaws B and C upon the nut G. Upon continued pressure on the handle D the jaws will all 115 the more firmly tend to seat upon the nut G to effect the removal or attachment thereof, as the case may be. The sliding of the pin 120

70 downwardly along the slot 36 is permitted, due to the fact that the handle shanks or fingers 53 and 54 are provided with the slots 65 and 66, which are transversely arranged 5 to the run of the slot 36. In order to adjust the wrench A for small objects, such as the nut F, it is merely necessary to disconnect the jaws B and C from the relation above mentioned, and slip the pin 70 through the aligning openings 16 of the jaw B, and assemble the parts as above described.

A very essential and important feature of the wrench consists in the provision of a spring 75, preferably of the leaf type, which 15 at one end thereof is secured in a recess 76 inwardly of the top surface 77 of the wrench handle body 50, as by means of a screw 78; said leaf spring 75 extending forwardly along the handle, and arcuating upwardly above the 20 space 55, and at its upper edge engaging at the under surface 79 of the lug 39; the spring 75 being normally flexed to urge the handle D in the direction which the same is forced 25 during an application for manual operation of the wrench. This tendency of the spring 75 is to urge the jaws B and C together into a clamping engagement about the article which is between the jaw faces 11 and 26. The spring 75 therefore gives a ratchet effect 30 to the wrench A, in that at the periods between the application of pressure for movement of a nut or bolt, the spring 75 will take effect to clamp the jaws against the article to be removed or placed, so that the wrench A 35 may be used with an oscillating effect; the spring 75 making sure that the jaws are in proper position to grip the nut or bolt as the handle and wrench are swung to a return position.

40 From the foregoing description of this invention it is apparent that a novel type of wrench has been provided, in that the parts are relatively simple, and durably and efficiently assembled to provide a wrench capable of quick adjustment, over a wide range. It will quickly and efficiently grasp the work, with a tendency to tighten the jaws as the application is made upon the handle, and upon release or return movement of the wrench about the nut or bolt, the spring 75 insures that the jaws are in proper position to grip the object and prevent their slipping therefrom.

Various changes in the shape, size, and arrangement of parts may be made to the 55 form of invention herein shown and described, without departing from the spirit of the invention or the scope of the claims.

I claim:

60 1. A wrench comprising a jaw structure including a body portion having oppositely disposed guide grooves therealong inwardly of the sides thereof and a laterally extending jaw head, said body being provided with a slot longitudinally communicating with

said grooves, a second jaw structure including a jaw head with a pair of spaced parallel shanks provided with aligning openings therein, said second mentioned jaw structure being adapted to straddle the body portion 70 of the first mentioned jaw structure with the shanks of the second mentioned jaw structure slidably retained in the grooves of the body of the first mentioned jaw structure to align the openings of the second mentioned jaw structure shanks with the slot of the first mentioned jaw structure, a handle bifurcated at its forward end to provide a pair of spaced fingers, means pivotally connecting said fingers at their forward ends on a fixed axis with the first mentioned jaw structure, and a pin pivotally and slidably connected with the fingers of said handle and extending through the openings and slot of said jaw structures, whereby upon oscillatory movement of the handle with respect to the jaws the latter will be moved toward and away from each other.

2. A wrench comprising a jaw structure including a body portion having oppositely disposed grooves therealong and a laterally extending jaw head, said body being provided with a slot longitudinally communicating with said grooves, a second jaw structure including a jaw head with a pair of spaced parallel shanks provided with aligning openings therein, said second mentioned jaw structure being adapted to straddle the body portion of the first mentioned jaw structure with the shanks of the second mentioned jaw structure sliding in the grooves of the body of the first mentioned jaw structure to align the openings of the second mentioned jaw structure shanks with the slot of the first mentioned jaw structure, a handle bifurcated at its forward end to provide a pair of spaced fingers, means pivotally connecting said fingers at their forward ends with the first mentioned jaw structure, means pivotally and slidably connecting the fingers of said handle through the openings and slots of said jaw structures, whereby upon oscillatory movement of the handle with respect to the jaws the latter will be moved toward and away from each other, and spring means 100 associated between the handle and the first mentioned jaw structure normally urging the handle in such direction as to tend to move the jaws into proximate relation.

3. A wrench comprising a jaw provided with a slot therein, a second jaw slidably connected with the first mentioned jaw having transverse openings aligning with the slot, a handle pivotally connected with the first mentioned jaw and having a slot therein transversely arranged with respect to the slot of the first mentioned jaw and aligning therewith and with the opening of the second mentioned jaw, a pin connected through said aligning slots and openings at a point 115 120 125 130

spaced from said pivotal connection of the handle with said first mentioned jaw whereby upon oscillative movement of the handle with respect to the first mentioned jaw the 5 pin will ride along said slots and urge the second mentioned jaw toward or away from the first mentioned jaw, and spring means connected between the handle and the first mentioned jaw normally urging the handle 10 in such relation to said jaws as to cause a proximate gripping movement of the jaws with respect to each other.

4. In a wrench of the class described the combination of a jaw structure including a 15 body provided with a pair of parallel oppositely disposed straight grooves and including a laterally extending jaw head provided with a transverse opening therethrough, said body being provided with a longitudinally ex- 20 tending slot therethrough, a second jaw structure including a jaw head and a pair of spaced straight parallel shanks provided with a series of transversely aligning openings therethrough adapted to align with said 25 slot when the shanks of the second mentioned jaw structure are slidably mounted in the grooves of the body of the first mentioned jaw structure, a wrench handle in-

cluding a pair of spaced fingers, at their ends provided with aligning openings and 30 inwardly of their ends being provided with a pair of transversely aligning slots, a pin pivotally mounting the fingers through the openings thereof and through the opening of the jaw head of the first mentioned structure, and a pin transversely connected through the aligning slots of the fingers of 35 said handle and through a pair of the series of openings of the shanks of said second mentioned jaw and through the slot of the first mentioned jaw structure whereby to 40 connect the jaws with the handle so that upon movement of the handle the jaws will be proximately moved.

5. In a wrench the combination of a jaw 45 provided with a shank having a slot therealong, a second mentioned jaw including a shank having a series of openings adapted to align with said slot, a handle, means pivotally connecting the handle to the first 50 mentioned jaw, and a detachable pin structure pivotally and slidably connecting the handle to any of the openings of said second mentioned jaw and through the slot of the first mentioned jaw.

NATALE SALVUCCI.
